F. C. HOBBS.

BILLIARD COUNTER.

APPLICATION FILED NOV. 15, 1910.

1,031,266.

Patented July 2, 1912.

UNITED STATES PATENT OFFICE.

FRANK C. HOBBS, OF NEW YORK, N. Y., ASSIGNOR TO THE BRUNSWICK-BALKE-COLLENDER COMPANY, OF NEW YORK, N. Y., A CORPORATION OF NEW YORK.

BILLIARD-COUNTER.

1,031,266.

Specification of Letters Patent.

Patented July 2, 1912.

Application filed November 15, 1910. Serial No. 592,494.

To all whom it may concern:

Be it known that I, FRANK C. HOBBS, a citizen of the United States, residing in the city of New York, in the county of New York and State of New York, whose post-office address is care The Brunswick-Balke-Collender Company, 29-35 West Thirty-second street, New York, N. Y., have invented a new and useful Improvement in Billiard-Counters, of which the following is a specification, reference being had to the accompanying drawing, forming a part thereof.

My invention relates to devices for registering the scores of the players at the game of billiards, and to that class or type of devices for keeping the count, which consists in a "string" of buttons or movable units strung on a taut wire, usually located over-head in the billiard room and over the table, where the players can conveniently reach it with the playing end-portions of their cues, to "shove up" the buttons, to mark each score made—in a manner well known. And as is also well known, the billiard counter or marker, of this, almost universally employed, type, comprises two sets of slidable buttons or markers strung on the same wire and adapted to be moved thereon, each set comprising enough members to mark the sum of a whole game of usually, one hundred points; and the two sets being differently colored, usually, one being white and the other black, to respectively mark, or keep tally of the scores of the several players, who use, respectively, the "white" and the "spot" cue-balls. In the use of this well known, and generally employed type of counter, or registering device, a long recognized practical objection to it lies in a liability of a button getting broken, now and then, and consequently detached from the wire, and the troublesome replacement of the broken-off button by a new one. And this objection to this type of billiard counter has led to the devisement, heretofore, of various constructions of substitute buttons, which can be applied to the wire of the string without taking down the latter—which is a troublesome job.

The buttons are, and have been invariably composed of wood; of disk-like shape; and whenever one is broken (by being suddenly

or roughly "shoved up" with the cue of a heedless game player) to replace it by a 55 duplicate, the wire has to be detached from its anchorage; some of the others unstrung; and a new one strung on; all of which involves much trouble. Hence, as I have said, substitute wooden buttons have been devised 60 (and some of them patented long ago) made in separable parts, so that they may be put onto the wire and the parts reunited thereon, without taking down the string. But such expedients, to avoid the great trouble 65 alluded to, have not for some reason ever gone into use, that I know of.

I propose to provide for use a string counter, the buttons, or units of which, strung on the wire, as usual, shall be non-breakable, so to speak; and at the same time afford for use a counter, of this type, which shall be of unique appearance and which, in other respects, shall be more desirable than any string counter heretofore made. And 75 to these ends and objects my invention may be said to consist, primarily, in a string counter, the units or "buttons" of which are composed of sheet metal and which, hence, cannot be split, or broken, so as to 80 become detached from the wire—no matter how roughly they may be handled, in counting the game;—and, secondarily, in other details of construction of the string counter; as will be hereinafter fully described; and 85 as will be most particularly pointed out in the claim of this specification.

To enable those skilled in the art to which my invention relates, to make and use a string counter embodying, either wholly or 90 partially, my invention, I will now proceed to more fully describe the latter by reference to the accompanying drawing, forming part of this specification; and in which I have shown my said invention carried out 95 in that form in which I have, so far, successfully practiced it; though modifications in the details of construction may, of course, be made without departing from the spirit of the main, or primary feature of the invention.

In the drawing Figure 1 is a partial side elevation of a string counter fully embodying my invention; drawn to a scale of full size; but with portions of the string broken 105 out and the remaining portions moved

nearer together (endwise of the string) in order to draw the view within the prescribed space, of a Patent Office drawing. Fig. 2 is a partial top view showing only 5 one end-portion of the taut wire and the device by which this end of the string is anchored to the room wall. Fig. 3 is a similar view of the other end-portion of the string, to illustrate particularly the 10 take-up, or tightening device by which this end of the string wire is securely fastened to the room wall, and may be drawn and kept taut. Fig. 4 is a detail view showing one of the disk-like metallic buttons, detached, 15 and, in edge-view, one of the pendant number tags seen (as No. "40") at Fig. 1. Fig. 5 is a detail view, on an exaggerated scale (about double full size) illustrating how are made the struck-up sheet metal two 20 parts composing, when united, one of my improved counter buttons; and Fig. 6 is a detail view, on the same enlarged scale, showing in diametric section (the same as Fig. 5) the completed metallic button produced by the union of the two parts shown 25 separately at Fig. 5. And in the several figures the same part will be found always designated by the same letter of reference.

D is the string wire on which all the 30 counter buttons M, are strung and which has its opposite ends secured or anchored to the room walls, by means of the novel fastening devices seen, respectively, at the left hand and right hand sides of Fig. 1. The 35 anchoring device at the left is composed of a metallic stand A, such as shown, the foot portion A² of which is made fast, by wood screws A³ preferably, to a wooden block b which, in turn, is fastened, by screws b' to 40 the wall. And this metallic stand carries, pivotally mounted therein, at a², a cam-lever A', (see Fig. 1) the cam-like portion a, of which coacts, when the lever is turned down into the position in which it is shown, (by 45 the application of hand power to its vibratory end a³) to force the end of wire D downward and buckle or bend it into the oblong aperture in the bottom plate of the stand; so as to securely hold the wire 50 against any endwise movement. The other end of the string wire D is wound or turned around on the periphery of a take-up drum G; into an aperture of which periphery the end of the wire is bent at g, (see Fig. 1) and 55 which drum is axially mounted in the vertical sides of the metal stand F; so that the protruding polygonal end I of its axis may be grasped by a key or wrench, to wind up the end of the wire and draw and hold fast 60 the latter in a taut condition. And on the end of the drum is a fast ratchet-wheel H, with which engages a pawl J, as shown, to hold fast on the ratchet. Preferably, the metal, drum-carrying, stand F is fastened, by wood screws f' (that pass through

its rear plate portion f) to a wooden block k' which, in turn, is fastened to the room wall L, as shown.

On the wire D are fastened, by set-screws e, the usual stop-collars E, against which the sliding counters M abut, in the usual manner; a pair being located at the vicinity of the middle of the string, lengthwise, against which to shove up the counters (of both the white and dark buttons) in marking a count made; and two at the vicinity of the ends of the wire to shove the sets of buttons back again ready for use as counters. Each one of the slidable buttons M is composed of sheet metal, pressed in dies or spun up, into the final shape shown, which, of course, is such that when they are strung on the wire D, with their hub-like portions in contact, there will be a sufficient space between their disk-like parts to permit the ready moving of one (or more) buttons in the usual manner, by the use of the end portions of a player's cue. And each of these metallic buttons M, I preferably construct out of two sheet metal parts previously struck up, or in any manner made into the shapes seen at Fig. 5.

Where the right hand part comprises the disk-like portion m', with its turned over bead-like part m⁶, and peripheral portion m⁷; and the hollow hub-like part m⁸ with its reverse central inwardly projecting hub m⁴, the bore m⁵ of which is to form part of the eye through which the string wire D passes. And where the left hand portion, 95 comprises the disk-like portion m²; (the perimeter m of which is to be inclosed within the parts m⁶ m⁷ of the right hand part in the completed device) also the same hub-like part m³, inverted hub m⁴, and eye m⁵ 100 of the right hand part of this figure. And when these two parts are united, in the juxtaposition seen at Fig. 6, by upsetting or spinning-over the peripheral portion m⁸ to embrace the perimeter of m², in the formation 105 of the bead-like perimeter m⁸ of the completed device, the result is the improved metallic button seen full size at Figs. 1 and 4.

The number tags such as seen at Figs. 1 and 4, I make also of sheet metal, preferably; but the novel characteristic of my number tag lies in the attachment of the tag, pivotally, to the wire instead of having it, as heretofore in string counters, made fast to one of the counter buttons. I contemplate the making of these number tags in some one of several ways, as to its detail structure, and of various metallic or other substances; but always pivotally attached to the wire of the "string." And at Fig. 1, I have shown two detail constructions, in one of which, (see No. "40" and also Fig. 4), the tag is pendants connected with the wire D by means of two wire loops, or oblong links P, that, as plainly shown, couple 115

the eyes of the tag with the wire D; and in the other of which, the stock of the sheet metal tag has two upward extensions each of which has its end looped, or bent around the 5 string wire at n'.

Of course, the numbers Q on the tags may be embossed thereon, or otherwise produced, and, in practising my invention these tags may be made of different colored metals for 10 the "white" and "black" strings respectively; and by various combinations of differently colored tags and buttons I am able to produce strings to represent counters for the two players of different appearances.

15 Without meaning to restrict myself, in practising my invention, to any of the precise detail of structure shown, with reference to the primary part, what I claim as

new and desire to secure by Letters Patent is:—

In a string billiard counter, the combination with the series of buttons; and the wire on which they are strung, of depending number-tags flexibly and slidably arranged on said wire, and that are slidably moved 25 thereon by the buttons which they respectively designate, but which are detached from said buttons; all in substantially the manner and for the purposes set forth.

In witness whereof, I have hereunto set 30 my hand this 12th day of November, 1910.

FRANK C. HOBBS.

In the presence of—

W.M. H. LANSMITH, Jr.,
M. CORCORAN.
